No. 709,153.

J. J. HYNDING.

Patented Sept. 16, 1902.

GATE.

(Application filed May 26, 1902.)

(No Model.)

UNITED STATES PATENT OFFICE.

JESSE JOHANSEN HYNDING, OF FERNDALE, CALIFORNIA.

GATE.

SPECIFICATION forming part of Letters Patent No. 709,153, dated September 16, 1902.

Application filed May 26, 1902. Serial No. 109,070. (No model.)

To all whom it may concern:

Be it known that I, JESSE JOHANSEN HYNDING, a citizen of the United States, residing at Ferndale, in the county of Humboldt and State of California, have invented a new and useful Gate, of which the following is a specification.

The invention relates to improvements in gates.

10 The object of the present invention is to improve the construction of swinging gates and to provide a simple, inexpensive, and efficient one capable of being readily operated at a distance from either side of it to enable 15 it to be opened and closed by a person on horseback or in a vehicle.

The invention consists in the construction and novel combination and arrangement of parts hereinafter fully described, illustrated 20 in the accompanying drawings, and pointed out in the claims hereto appended.

In the drawings, Figure 1 is a side elevation of a gate constructed in accordance with this invention. Fig. 2 is a vertical sectional view of the gearing for actuating the gate. Fig. 3 is an elevation of the same. Fig. 4 is a detail view of the keeper. Fig. 5 is a detail view illustrating the manner of hinging the bottom of the gate. Fig. 6 is a detail view 30 on the line xx of Fig. 2, illustrating the construction of the sector-shaped plate.

Like numerals of reference designate corresponding parts in all the figures of the drawings.

35 1 designates a cap designed to be fitted on the inner end bar 2 of a gate 3 and provided with a short vertical shaft 4, which may be fixed to the cap in any suitable manner and which is provided at its upper end with a pinion 5.

40 The lower end of the bar 2 of the gate has a depending journal 6, fitted in a bearing-recess 7 of a bracket 8 and provided with a shank which is embedded in the lower end of the bar 2. The shank extends upward 45 from the washer 9, and the lower end of the bar 2 is supported by a band 10.

The pinion 5, which has bevel-teeth, may be fixed to the upper end of the shaft 4 in any suitable manner, and it meshes with a 50 segment or curved series of teeth 12, which are formed integral with a tapering approximately sector-shaped plate 13, provided at its

lower end with an eye 14, arranged on a rounded bearing portion 15 of a bolt 16. The bolt 16 passes through an upright or hinge-post 17, upon which the bearing-bracket 8 is mounted. The rear end of the bolt 16 is threaded, and the portion which passes through the post is reduced to form a shoulder 18, against which abuts a washer 19, 55 which also fits against the post 17 to space the oscillatory sector shaped plate 13 therefrom. The front end of the bolt is provided with an eye 20 to receive the shaft 4, which hinges the top of the gate, and the rear threaded end of the bolt is engaged by a nut. The upper portion of the sector-shaped plate having the teeth is arranged at an inclination, as clearly shown in Fig. 2, to correspond with the bevel of the pinion, and the sector-shaped 70 plate is provided with a central vertical extension 21, and it has a lug or enlargement 22. The extension or arm projects vertically from the sector-shaped plate, and the lug is arranged at the back of the plate directly 75 above the eye 14, and its rear face is arranged in the same vertical plane as the rear face of the extension 21. The said extension 21 and the lower portion of the plate 13 are perforated for the reception of upper and lower 80 bolts 23 and 24, which secure the lower portion of an arm 25 to the plate 13. The fastening devices preferably consist of bolts, as shown, and the upper end of the arm or bar is curved outward over the pinion and is 85 extended upward, as clearly shown in Fig. 2. The upper end of the bar or arm 25 is perforated for the reception of a bolt or rivet, which forms a pivot 26 for a latch-operating 90 lever 27. The latch-operating lever is arranged in an upright position, and its lower end is connected by a flexible connection 29 with a pivoted latch 30. The flexible connection may consist of a wire, cord, rope, cable, or the like, and it extends downward from the 95 latch-operating lever to a rear guide-pulley 31 and then forward or outward to a front guide-pulley 32. The guide-pulleys 31 and 32 are mounted upon the top of the gate, and the front one is located directly above the 100 latch 30. The latch is pivoted at its inner end, and the upper end of the latch-lever is connected with suitable flexible connection 33, extending from opposite sides of the gate

and adapted to be pulled to oscillate the latch-lever and the arm 25. When either of the operating-ropes is pulled, the latch-lever will be first oscillated and the arm 25 operated to release the gate, and the arm 25 will be swung toward the operator, thereby swinging the segment and opening the gate away from the operator. After passing through the gateway the other operating-rope is pulled and the gate is closed. When the gate is open, the latch engages a supplemental keeper of the ordinary construction and when closed it engages a pivoted double keeper consisting of a plate 34, mounted on a latch-post 35, and a pair of inclined blocks or pieces 36, pivoted near their upper or inner ends by bolts 37 or other suitable fastening devices and supported in an inclined position by bolts 38, having nuts forming inclined upper faces, as clearly shown in Fig. 4. When the gate closes, the latch depresses the inner end of the adjacent pivoted block or piece 36 and is prevented from swinging past the keeper by the other pivoted block or piece. The plate 34 of the keeper is provided with a central recess, and the blocks or pieces extend upward sufficiently to securely hold the gate in its closed position.

It will be seen that the gate is simple and comparatively inexpensive in construction, that it is easily operated, and that the operating mechanism may be readily applied to an ordinary gate. It will also be seen that the gearing is arranged to support the gate, and that it cannot get out of mesh by any tendency of the gate to sag, and that it is compactly arranged above the rear end bar of the gate.

The sector-shaped plate is provided at opposite sides of the central extension with vertical flanges 39, extending downward to the eye 14 and receiving the rearwardly-extending lug and forming a partial socket for the lower end of the arm or bar 25.

45 What I claim is—

1. In a device of the class described, the combination with a swinging gate, and a hinge-post, of a cap mounted on the gate and provided with a vertical shaft forming a pintle, a bolt secured to the hinge-post and provided adjacent to the same with a bearing portion and having an eye receiving the said shaft, a pinion mounted on the upper end of the shaft, a plate provided with an eye arranged on the bearing portion of the bolt, said plate being also provided with a curved series of teeth

meshing with the said pinion, an arm extending from the plate, and a pivoted latch-operating lever mounted on the arm, substantially as described.

2. In a device of the class described, the combination with a swinging gate and a hinge-post, of a cap mounted on the gate and provided with a short vertical shaft, a bolt extending from the hinge-post and provided with a bearing portion and having an eye located beyond the bearing portion and receiving the vertical shaft, a bevel-pinion mounted on the shaft, a sector-plate provided at its lower end with an eye to receive the bearing portion of the bolt and having an extension at the top, said sector-plate being also provided with an inclined upper portion having a curved series of teeth meshing with the pinion and the lower portion of the sector-plate being provided with a rearwardly-extending lug, an arm secured to the lug and to the extension and extending forward and upward over the pinion, and a latch-lever fulcrumed on the upper end of the arm, substantially as described.

3. In a device of the class described, the combination with a hinge-post, and a gate, of a bearing-bracket supporting the bottom of the gate, a cap secured to the gate at the top thereof and having a vertical shaft, a bevel-pinion secured to the upper end of the vertical shaft, a horizontal bolt mounted on the post and having an eye receiving the shaft, said bolt being also provided between the eye and the post with a bearing portion, a sector-plate provided at its lower end with an eye to receive the bearing portion of the bolt and having an inclined portion provided with teeth meshing with the pinion, said plate being extended at the top and provided at the rear with vertical flanges and having a lug at the lower portions thereof, an arm secured to the plate and arranged between the flanges thereof, a latch mounted on the gate, a latch-lever fulcrumed on the arm and connected with the latch, and flexible connections extending from the latch-lever, substantially as described.

In testimony that I claim the foregoing as my own I have hereto affixed my signature in the presence of two witnesses.

JESSE JOHANSEN HYNDING.
